US0D1070924S

(12) **United States Design Patent** (10) **Patent No.:** **US D1,070,924 S**
(45) **Date of Patent:** **** Apr. 15, 2025**

(54) **PORTABLE PUMP WITH A MULTIPLE REGISTER PRESSURE GAUGE**

(71) Applicant: **KKU/ISS, Inc.**, Travelers Rest, SC (US)

(72) Inventor: **Robert Fox**, Travelers Rest, SC (US)

(73) Assignee: **KKU/ISS, Inc.**, Travelers Rest, SC (US)

(**) Term: **15 Years**

(21) Appl. No.: **29/878,982**

(22) Filed: **Jun. 29, 2023**

Related U.S. Application Data

(63) Continuation of application No. 17/866,153, filed on Jul. 15, 2022, now abandoned, and a continuation of application No. 17/344,310, filed on Jun. 10, 2021, now abandoned.

(57) **CLAIM**

The ornamental design for a portable pump with a multiple register pressure gauge, as shown and described.

DESCRIPTION

FIG. 1 is a top perspective view of my new design of a portable pump with a multiple register pressure gauge; FIG. 2 is a partial, enlarged, perspective view of the multiple register pressure gauge of the portable pump as in FIG. 1; FIG. 3 is a top plan view of the portable pump with the multiple register pressure gauge as in FIG. 1; FIG. 4 is a left side, elevational view of the portable pump with the multiple register pressure gauge as in FIG. 1; FIG. 5 is a right side, elevational view of the portable pump with the multiple register pressure gauge as in FIG. 1; FIG. 6 is a front elevational view of the portable pump with the multiple register pressure gauge as in FIG. 1; FIG. 7 is a rear elevational view of the portable pump with the multiple register pressure gauge as in FIG. 1; and, FIG. 8 is a bottom plan view of the portable pump with the multiple register pressure gauge as in FIG. 1. The dashed lines in the figures are for illustrative purposes only and form no part of the claimed design.
